UNITED STATES PATENT OFFICE.

EDWIN F. ALLBRIGHT, OF ATLANTIC, MASSACHUSETTS, ASSIGNOR TO ADAMS-POND COMPANY, INC., OF BOSTON, MASSACHUSETTS, A CORPORATION OF MASSACHUSETTS.

CONCRETE CONSTRUCTION.

1,353,373.

Specification of Letters Patent. Patented Sept. 21, 1920.

Application filed July 30, 1919. Serial No. 314,347.

To all whom it may concern:

Be it known that I, EDWIN F. ALLBRIGHT, a citizen of the United States, residing at Atlantic, in the county of Norfolk and State of Massachusetts, have invented an Improvement in Concrete Construction, of which the following description, in connection with the accompanying drawings, is a specification, like characters on the drawings representing like parts.

The invention to be hereinafter described relates to concrete construction, and is an improvement upon the construction shown, described and claimed in Letters Patent No. 1,307,031, granted to me June 17, 1919.

The concrete construction of said patent comprises a continuous concrete slab having solid panels resting on columns, and bays between said solid panels having at their under sides transversely extending ribs with domes or recesses distributed therein to the solid panels. In the production of this construction, domed pans or forms are employed, having outwardly extending flanges, the pans being adapted to be arranged in rows with the outwardly extending flanges thereof in engagement to determine the spacing thereof. The pans are supported by shoring comprising stringers on which the flanges of the pans rest, beams supporting the stringers, and posts disposed at appropriate intervals to support the beams. The concrete is poured into spaces between the pans, and in sufficient amount above the tops of the pans to furnish a concrete slab of the depth required.

To reinforce the slab, crossing series of reinforcing members are provided arranged in pairs. Certain of said members have portions located in the lower portions of the ribs of the bays, portions inclining upwardly at the edges of the bays, and end portions in the upper surface portions of the margins surrounding the bays. Others of said members have portions in the lower portions of the ribs of the bays and continue without deflection into the margins surrounding the bays. The arrangement of these reinforcing members is such that the members of adjacent bays overlap in the margins surrounding the bays.

This is a good reinforcing system for the purposes, but many of the reinforcing members must be specially bent before being placed, and care must be taken that they

are bent at the proper points to conform to the areas of the bays. Also, it is difficult properly to locate and support these bent members before the concrete is placed, and to maintain these members in their proper positions while the concrete is being placed.

The purpose of the present invention, therefore, is to provide a cheaper, simpler reinforcing system of members which may be readily located in their proper position before and during placing of the concrete, and which will furnish efficient reinforcement for the concrete. In carrying the invention into practical effect, straight reinforcing members may be employed throughout, thereby eliminating the necessity for employment of special forms of reinforcing members, and enabling the reinforcing members to be compactly arranged for shipment or storage.

With the aforesaid and other objects in view, the character of the invention will be best understood by reference to the following description of one good form thereof shown in the accompanying drawings, wherein:

Figure 1 is a plan view showing the system of reinforcing members embodying the invention in relation to the pans or forms before the concrete is placed;

Fig. 2 is a vertical section taken on line 2-2 of Fig. 1 after the concrete is placed;

Fig. 3 is a vertical section taken on line 3-3 of Fig. 1 after the concrete is placed;

Fig. 4 is a perspective view of a system of reinforcing rods or members for a portion of the slab;

Fig. 5 is a perspective view of a detail to be referred to; and

Fig. 6 is a perspective view of one of the pans or forms.

Referring to the drawings, and more particularly to Fig. 1, to produce the domes or recesses in the under side of the bays, pans or forms 1 are provided having outwardly extending flanges 3, the pans or forms being assembled with their flanges engaging one another to determine the spacing thereof. Suitable means may be provided to support the pans or forms, in the present instance, comprising stringers 5 on which the flanges of the pans or forms rest, beams 7 extending transversely to and supporting the stringers, and posts 9 disposed at suitable intervals to support the beams. Suitable

forms 11 are also provided for the production of solid panels above the columns.

The system of reinforcing members for the concrete slab, in the present instance of the invention, comprises crossing series of reinforcing rods or members 13, preferably arranged in pairs and located in the lower portions of the bays between the solid panels. These rods or members are straight throughout, and may terminate substantially at the edges of the bays. Certain of these rods or members, such, for example, as alternate rods or members may extend beyond the others somewhat into the margins adjacent the bays.

Series of rods or members 15 may be provided, preferably in pairs and located in the lower portions of the ribs extending from panel to panel in the margins surrounding the bays, and located between adjacent bays. These rods or members may terminate substantially at the edges of the solid panels, and preferably certain of these rods or members extend somewhat beyond others into the solid panels.

The series of rods or members 13 and 15 described will furnish the necessary reinforcement for the lower surface portion of the slab, which experiences tension stresses.

30 A series of relatively short rods or members 17 may be provided, preferably arranged in pairs in the upper surface portions of the margins surrounding the bays of the slab. These rods or members may extend transversely to the rods or members 15, and preferably certain of said rods or members may project beyond others into the adjacent bays. These relatively short rods or members will furnish the necessary tension 40 reinforcement for the upper surface portions of the margins surrounding the bays. Suitable means may be provided to support these relatively short reinforcement rods or members the proper distance above the flanges of the pans or forms. This means, in the present instance of the invention, comprises briquets 19 of concrete or other suitable material which may be suitably formed to fit between and rest on adjacent pans or 50 forms. The short rods or members may rest on these briquets, and be supported thereby at the proper elevation above the flanges of the pans or forms, and these briquets may remain in the concrete and form 55 a part of the final construction.

Crossing series of reinforcing rods or members 21 may be provided in the upper surface portions of the solid panels above the columns, and preferably may extend somewhat beyond the edges of said solid panels into the bays and margins surrounding the solid panels.

In some instances it may be desirable to provide further reinforcement at the junction of the bays with the solid panels to

take care of shear stresses. In the present instance for this purpose, stirrups 22 (Fig. 4) are provided adjacent the solid panels and conveniently formed to present ends adapted to rest upon the tops of the pans or forms adjacent the solid panels. The bottoms of the stirrups may desirably serve to contribute to the support of the reinforcing rods or members which terminate adjacent the edges of the solid panels.

The reinforcing rods or members should be supported somewhat above the flanges and tops of the pans or forms, in order that said rods or members shall be inclosed in the concrete. Supporting devices for reinforcing rods or members are well known in the art, and therefore, it is unnecessary to show the same herein.

After the system of reinforcing rods or members has been located as described, the concrete may be poured around the pans or forms and on the forms for the solid panels to the depth required. After the concrete has stood three or four days, it will have hardened sufficiently to permit the majority of the pans or forms to be removed. Certain of the pans or forms at suitable intervals may remain in place and may continue to be supported by posts to furnish the necessary support for the slab until it has finally hardened.

The final construction will comprise columns 23 supporting a slab comprising solid panels 25 resting on the columns, bays 27 between the solid panels, and margins 29 between adjacent bays. The domes or recesses will be formed on the under sides of the bays or margins. The system of reinforcing rods or members and the briquets will be inclosed in the concrete, and the system will furnish the requisite tension reinforcement for the slab throughout.

By my invention a simple and efficient reinforcing system is provided for the slab, the rods or members may be of standard construction, and since all of the rods are straight, it is merely necessary to cut the same into lengths required without the necessity for bending or otherwise specially shaping the same. Also, by this system important economies are obtained in the amount of reinforcement required, and in the time and labor required to position the same in readiness to have the concrete placed about the system.

It will be understood that the invention is not limited to the specific embodiment shown, and that various deviations may be made therefrom without departing from the spirit and scope of the appended claims.

What is claimed is:—

1. In concrete construction, the combination of columns, a concrete slab having solid panels resting on said columns, and bays between said solid panels having at their

under sides domes or recesses distributed therein to the margins of the solid panels with transversely extending ribs between said domes or recesses, crossing series of 5 straight reinforcing members in the lower portions of the ribs in the central areas of the bays, series of straight reinforcing members in the lower portions of the ribs extending from panel to panel in the margins of 10 the bays, series of straight reinforcing members in the upper surface portions of the margins of the bays and arranged transversely to the reinforcing members extending from panel to panel, and crossing series 15 of straight reinforcing members located in the upper surface portions of the solid panels.

2. In concrete construction, the combination of columns, a concrete slab having solid 20 panels resting on said columns, and bays between said solid panels having at their under sides domes or recesses distributed therein to the margins of the solid panels with transversely extending ribs between 25 said domes or recesses, crossing series of reinforcing members located in the lower portions of the ribs in the central areas of the bays, certain of the members of each series projecting beyond others of said members 30 into the margins of the slab adjacent said bays, series of reinforcing members in the lower portions of the ribs extending from panel to panel in the margins of the slab, certain of the members of the latter series 35 being extended beyond others of said series into the solid panels, series of reinforcing members in the upper surface portions of the margins of the slab and extending transversely of said marginal portions, cer- 40 tain of the latter series of members being extended beyond others of said series into the bays at opposite sides of said margins, and reinforcing members located in the upper surface portions of the solid panels.

3. In concrete construction, the combination of columns, a concrete slab having solid panels resting on said columns, and bays between said solid panels having at their under sides domes or recesses distributed therein 45 to the margins of the solid panels with transversely extending ribs between said domes or recesses, crossing series of reinforcing members located in the lower portions of the ribs in the bays, series of short 50 rods located in the upper surface portions of the margins surrounding said bays between the solid panels and offset upwardly from the reinforcing members in said bays,

and reinforcing members located in the upper surface portions of said panels. 60

4. In concrete construction, the combination of columns, a concrete slab having solid panels resting on said columns, and bays between said solid panels having at their under sides domes or recesses distributed 65 therein to the margins of the solid panels with transversely extending ribs between said domes or recesses, crossing series of straight reinforcing members arranged in pairs in the lower portions of the ribs of the bays, series of relatively short reinforcing 70 members arranged in pairs in the upper surface portions of the margins at opposite sides of the bays, reinforcing members arranged in pairs in the lower portions of the 75 ribs in said margins and extending transversely to said relatively short members, and crossing series of reinforcing members in the upper surface portions of the panels above the columns. 80

5. In concrete construction, the combination of columns, a concrete slab having solid panels resting on said columns, and bays between said solid panels having at their under sides domes or recesses distributed 85 therein to the margins of the solid panels with transversely extending ribs between said domes or recesses, crossing series of straight reinforcing members located in the lower portions of the ribs of the bays, 90 series of straight reinforcing members located in the upper portion of the slab and extending transversely of the margins of the bays, and members for supporting said last series of members and adapted to bridge 95 adjacent pans or forms used in producing the domes or recesses.

6. In concrete construction, the combination of columns, a concrete slab having solid panels resting on said columns, and bays 100 between said solid panels having at their under sides domes or recesses distributed therein with transversely extending ribs between said domes or recesses, crossing series of straight reinforcing members in the lower 105 portions of the ribs of the bays, series of reinforcing members for the margins of the bays, series of reinforcing members in the upper portions of the panels, and stirrups adapted to rest on pans or forms used in the 110 production of the domes or recesses adjacent the solid panels to furnish shear reinforcement.

In testimony whereof, I have signed my name to this specification.

EDWIN F. ALLBRIGHT.
